CLAIM

The ornamental design for a nozzle, as shown and described.

DESCRIPTION

FIG. 1 is a top perspective view of the nozzle;

FIG. 2 is a front, elevation view thereof;

FIG. 3 is a rear, elevation view thereof;

FIG. 4 is a first side, elevation view thereof;

FIG. 5 is a second side, elevation view thereof;

FIG. 6 is a top, plan view thereof; and,

FIG. 7 is a bottom, plan view thereof.

The broken lines are shown for the purpose of illustrating environmental subject matter of an exemplary container and form no part of the claimed design.

1 Claim, 5 Drawing Sheets
